FLOYD DOW, OF WYANET, ILLINOIS, ASSIGNEE OF ONE-HALF TO JOHN C. RASMUSSEN,
OF WYANET, ILLINOIS.

CAR-SEAL.

1,112,123.

Specification of Letters Patent. Patented Sept. 29, 1914.

Application filed May 20, 1914. Serial No. 839,722.

To all whom it may concern:

Be it known that I, FLOYD Dow, a citizen of the United States, residing at Wyanet, in the county of Bureau and State of Illinois, have invented a new and useful Improvement in Car-Seals, of which the following is a specification.

My invention relates to an improvement in the class of car seals, in which the shackle is a strip of frangible sheet-metal (usually "tin"), bent upon itself and carrying on one end a hollow head, into which the opposite end of the strip is insertible to be held against withdrawal by automatically locking means in the head.

In the accompanying drawing, the views in which show the parts exaggerated beyond actual size, Figure 1 is a broken plan view of the shackle-blank; Fig. 2 is a section of the car seal on line 2, Fig. 3, showing the shackle broken away and in its condition before applying the seal; Fig. 4 is a plan section on line 3, Fig. 2, and Fig. 4 is a view like that presented by Fig. 2, but showing the insertible end of the shackle locked in the head.

The head 5 is formed of a rounded top provided with a recessed flange 6 about its edge and a bottom part having a flat base 30 and a flange 7 about its edge confined in the recessed flange 6 for securing together the two parts of the head. The flat base contains a central slot 8 of a width to permit the shackle 9 to pass through it. The shackle, which is a strip of tin so frangible that it will not withstand repeated bending without breaking, has an eye 10 formed in it near one end. Near the opposite end of the shackle is formed a rectangular cut 11, 35 and some distance from the latter a similar cut is formed. Between these cuts, at the same distance from each, slots 12 are provided having narrow elongated depressions or sockets 13 extending from their relatively 40 opposite sides; and between these slots a narrow elongated slot 14 is formed in the shackle centrally between its edges. The material severed by each cut 11 in the shackle is bent outwardly to a right-angle 45 to form a stop-shoulder 11^a, for the purpose hereinafter explained.

For assembling the parts to produce the car-seal in a form ready for application to its use, the two parts of the head are separate. The shackle is bent upon itself into

loop-form at a point midway between the two cuts 11, and the shackle is inserted at its relatively long and short ends through the slot 8 in the head-base until stopped by abutment against the latter of the shoulders 11^a. In this position of the parts the two slots 12 are opposite each other, as are also the sockets 13. A split locking ring 15, of light resilient wire, having its overlapping ends bent to project inwardly, as shown at 15^a, is then applied in a manner to introduce the ends 15^a into the sockets 13 and extend the ring through the bowed slot 14, as shown in Figs. 2 and 3. With the ends 15^a thus yieldingly confined in the sockets 13, 70 the ring is held under tension to clamp itself stably in place to be displaced for performing its locking function as hereinafter explained. The top member of the head is then applied to the base-member and the 75 flange 6 is clenched about the flange 7 to secure the two head members together.

To lock the seal, in applying it in the usual manner, the shackle is bent into loop-form to insert its end containing the eye 10 80 into the head through the base-slot 8. In thus inserting the shackle-end, it is guided between the portions of the shackle containing the openings formed at the cuts 11 by bending the sections to produce the shoulders 11^a; and when the inserted shackle-end abuts against the ring 15 in its path, the continued pressure withdraws the ring-ends 15^a 85 out of the sockets into registration with the slots 12, with which the eye 10 also then registers. The resilient action of the ring then springs its ends past each other through those slots and the shackle-eye, thereby causing the ring to lock the shackle end against withdrawal. 90

As will be seen, the described construction precludes the possibility of a false introduction of the inserted shackle-end into the head, since its only path into the latter is under the described central guidance 100 through the slot 8. It will also be apparent that the end of the shackle permanently in the head is secured therein without requiring any means for the purpose other than or separate from the shackle itself; that the 105 stability of the locking ring, before it is contracted by displacement in inserting the eye-containing shackle-end, and afterward when in its contracted condition wherein it is confined in the bowed slot 14, prevents the 110

ring from tilting into a position wherein that end of the shackle might be withdrawn between the overlapping ring-ends; that the confinement of the ring-ends in the sockets 5 prevents the ring, as by accidental jarring, from assuming its locking position, with the ends overlapping through the slots 12, wherein it would obstruct introduction of the eye-end of the shackle and thus render 10 the seal inoperative; and that the only way to undo the seal is to break the shackle by bending or twisting it apart, at the sections outside of the head which are weakened by openings formed by the cuts 11, though 15 this would leave the parts in the head to prevent insertion into the latter through the slot 8 of the broken shackle-ends (which insertion would tend to prevent detection), so that such breaking would inevitably lead 20 to detection of tampering with the seal. These and other advantages are afforded by my improved construction, which, besides, is comparatively simple and inexpensive to manufacture, involving only four 25 parts.

What I claim as new and desire to secure by Letters Patent is:—

A car seal comprising a hollow head provided with an insertion-slot, a shackle having an eye in one end and formed at its opposite end into a shouldered loop confined in the head and provided with a longitudinal slot extending into both of its separated legs, relatively opposite slots near the ends of the longitudinal slot and sockets in 30 said legs diverging to said relatively opposite slots, and a split resilient locking ring extending through both legs of said longitudinal slot and having in-turned ends 35 yieldingly confined in said sockets, the shackle extending from the head through 40 said insertion-slot and having its eye-containing end insertible into the head through said insertion-slot to release and actuate the locking ring.

FLOYD DOW.
